ABRASIVE HAND TOOL

Robert W. Martin, 1057 Pennington Road,
Trenton, N.J. 08618

Filed Feb. 24, 1969, Ser. No. 15,866

Term of patent 14 years

Int. Cl. D8—02

U.S. Cl. D8—90

FIG. 1 is a perspective view illustrating an abrasive hand tool embodying my new design;

FIG. 2 is a side elevation of the abrasive hand tool illustrated in FIG. 1; and

FIG. 3 is an end view of the abrasive hand tool illustrated in FIG. 1.

I claim:

The ornamental design for an abrasive hand tool, as shown.
